ADJUSTABLE JOINT FOR EXPANSIBLE FRAMES

Daniel A. Eberhardt, St. Louis, Mo.

Application September 27, 1948, Serial No. 51,431

2 Claims. (Cl. 287—58)

1

This invention relates to an adjustable joint, including a clamp or lock, for the members of an extensible frame such as a trouser creaser.

The invention relates to an improvement in a device disclosed in Patent No. 2,294,967, issued to Daniel A. Eberhardt, the present inventor. The invention is also an improvement in a device disclosed in his application Serial No. 792,398, filed December 18, 1947. The device of the present invention, while retaining some of the features of the first mentioned patent, employs a somewhat different structure with a different mode of operation. It distinguishes from the second device by a much simplified structure while retaining its mode of operation.

A summary statement of the invention can best be made by reference to the accompanying drawings and is deferred until after the following description of them.

Fig. 1 is a plan view of a trouser creaser embodying the invention;

Fig. 2 is a perspective view of an adjustable joint, with clamp or lock, included in said creaser;

Figs. 3 and 4 are end views of the joint shown in Fig. 2 and showing the relationship of the parts in clamping position and released position; and

Fig. 5 is a view similar to Fig. 3, showing the joint in a modified form.

While the invention is defined in the appended claims, a summary description of it, without intent of limiting it beyond that required by the claims, will assist in understanding them and the later detail description of the invention as it is embodied in a preferred structure.

The joint is for a pair of adjacent relatively slideable rod sections 11 and 12 which have spaced members or collars 13 for maintaining the sections 11 and 12 in sliding relationship and substantially contiguous but for a bowed portion 14 (Fig. 5), or 15 (in the other figures), in one rod, thereby providing a recess 16 between the rods.

A key 17, (Fig. 5) or 18 (in the other figures) has an orifice through which the rod 12 passes, and has a portion positioned in the recess 16. The key 17 or 18 has a bent portion at its inner end (lying within the recess 16) so constructed and arranged that the key is normally in an oblique position (Figs. 3 and 5) with respect to the rod 12. This prevents movement of the rod 12 to the right, as shown in the drawings. The inner end of the key, however, is so constructed as to permit relative movement of the rods in the opposite direction; that is movement of the

rod 12 to the left. By movement of the key toward a perpendicular position, free movement of the rods in either direction is permitted.

To construct the inner end of the key so that it will have the functions described, the key 17, in Fig. 5, which is the simpler construction, has a lug 19 bent over forming a shoulder 20. When the device is not under pressure or strain it assumes the oblique position shown in Fig. 5. Upon movement of the rod 12 to the right, the shoulder 20 will engage the inner surface of the bowed section 14, keeping the key 17 oblique and thereby cramping and locking the rod 12 against further movement. When, however, the rod 12 is moved to the left the end of the lug 19 will strike the inner surface of the bowed section 14, moving the key toward a perpendicular position on the rod 12, and permitting its movement in that direction.

Obviously the slightly more complex structure shown in Figs. 2, 3 and 4 will operate similarly. This structure is provided to prevent accidental overthrow of the key 18 to oblique clamping position by manual movement. In these figures the key 18 has a curved or arched portion 21 and a straight portion 22, which cooperates with corresponding shaping of the bowed portion 15 to secure this result.

A more detail description of the invention and of the embodiment illustrated in the drawings will assist in understanding and practicing the invention. It is shown as embodied in a trouser creaser, which is an extensible frame structure adapted to be inserted in the leg of a trouser when the trouser is damp and expanded to full open position. The purpose of the frame is to give shape to the trouser leg as it dries.

The creaser includes two cooperating members, a side member 25 which has inwardly extending arms or bars 11, and a side member 26 which has inwardly extending arms or bars 12. These members 25 and 26 with their arms 11 and 12 are preferably constructed of flat galvanized steel wire.

These members 25 and 26 with their inwardly extending arms are so arranged that an arm or rod section 11 and a rod section 12 are maintained in sliding relationship and substantially contiguous by means of spacing members or collars 13. These collars 13, as specifically shown, are secured to the end of a rod section and about an adjacent section to permit free sliding movement. That is to say, a collar 13, Fig. 2, is secured to the end of the rod section 11 and surrounds the rod section 12 in such a

manner as to permit the section 12 to slide freely therethrough.

A lock which has been previously summarily described, includes a bowed section 14 (Fig. 5) or a section 15 (in the other figures) in the rod section 11. It also includes a key 17 or 18 which cooperates with the inner surface of the bowed section to lock or release the rod section relative to each other in the manner intended.

In accordance with this invention the lock is so constructed that it permits the frame to be expanded without manipulation of the lock, while preventing a collapsing of the frame until the lock is manipulated. That is to say, it permits relative movement of the rod sections 11 and 12 in one direction while restraining them from relative movement in the other direction.

The key 17 or 18 has an orifice or aperture 27 which is slightly larger than the rod section 12 which passes through it and such as to permit the key to slide freely on the rod sections unless it is placed in a cramping position. Such a cramping position is assumed when the key is oblique to the rod section, as shown in Figs. 3 and 5. When the key is moved toward a perpendicular position the rod section 12 is free to move therethrough.

As previously described the inner end of the key (17 or 18) which lies within a recess 16 of the bowed section 14 (Fig. 5, or 15 in the other figures) is so constructed as to give the key a directional tendency. Thus when there is no stress upon the parts the key will lie as shown in Figs. 3 and 5, oblique to the rod section 12. If the frame is to be extended, the rod section 12 moved to the left as shown in the figures, the interior surface of the recessed or bowed portion 14 will strike the end of the lug 19 on the key 17 urging the key toward perpendicular position and permitting further movement. If the frame is to be compressed the interior surface of the bowed section 14 will contact the shoulder 20 holding the key in oblique position, thus cramping the key in the rod 12 and thereby locking the sections. Upon manual adjustment of the key toward a perpendicular position the rod sections 11 and 12 may be freed for relative movement.

The embodiment shown in Fig. 5 is the simpler construction. Under some circumstances, however, by reason of slightly defective workmanship or excessive pressure, the key 17 by manual adjustment can be overthrown thereby locking the sections together when such is not intended. A slightly more complex structure, shown in Figs. 2, 3, and 4, substantially eliminates this possibility. Otherwise, however, the key 18 functions in the same manner as described in connection with the key 17 in Fig. 5. The key 18 has a curved portion 21 which fits a correspondingly curved portion 23 in the bowed section 15. There is also a horizontal section 29 in the bowed section 15, the inner surface of which forms a bearing for the straight portion 22 on the end of the key 18.

Various changes may be made in the details of construction, within the scope of the appended

claims, without departing from the spirit of this invention. Parts of the invention may be used without the whole and improvements may be added while retaining the combination and advantages of this invention.

I claim:

1. An adjustable joint for an expandable frame comprising a pair of adjacent relatively slidable rod sections, spaced members for maintaining said sections in sliding relationship and substantially contiguous but for a bowed portion in one rod providing a recess between the rods, and a key having a portion positioned in said recess formed by the bowed portion in one rod and having an orifice through which the other rod passes, the key having a lug at its inner end positioned angularly with respect to the remaining portion of the key and thereby forming a shoulder on the inner end of the key, the inner end of the key and the bowed portion being so constructed and arranged that the key is normally held oblique with respect to the other or straight rod, the shoulder engaging the inner surface of the bowed portion to cause such obliquity and thereby clamp and hold the rods against relative movement in one direction, but in movement of the rods in the opposite direction the lug engages the inner surface of the bowed portion, moving the key toward perpendicular position, thereby permitting free relative movement of the rods in that direction.

2. An adjustable joint for an expandable frame comprising a pair of adjacent relatively slidable rod sections, spaced members for maintaining said sections in sliding relationship and substantially contiguous but for a bowed portion in one rod providing a recess between the rods, and a key having a portion positioned in said recess formed by the bowed portion in the one rod and having an orifice through which the other rod passes, the key at its inner end having a bent portion so constructed and arranged with reference to the bowed portion that it engages the inner surface of said bowed portion to hold the key oblique with respect to the other or straight rod to clamp and hold the rods against relative movement in one direction only, but permitting the manual movement of the key toward a perpendicular position to permit free relative movement of the rods in either direction; the inner end of the key having a curved portion and a straight portion cooperating with the bowed portion shaped correspondingly to the key to prevent overthrowing the key to oblique clamping position by manual movement.
